UNITED STATES PATENT OFFICE.

ELDRED MARSHEL HIBBLER, OF IRIS, MISSISSIPPI.

CANE-KNIFE.

982,674.

Specification of Letters Patent. Patented Jan. 24, 1911.

Application filed August 4, 1909. Serial No. 511,220.

To all whom it may concern:

Be it known that I, ELDRED M. HIBBLER, a citizen of the United States, and a resident of Iris, in the county of Coahoma and State of Mississippi, have made certain new and useful Improvements in Cane-Knives, of which the following is a specification.

This invention is an improvement in cane knives, and consists in certain novel constructions and combinations of parts as will be hereinafter described and claimed.

In the drawing Figure 1 is a side view, partly in section, of a cane cutter embodying my invention. Fig. 2 is a detail perspective view of the butt end of the blade. Fig. 3 is a detail section on about line 3—3 of Fig. 1. Fig. 4 is a detail perspective view of one of the blade holding sections, and Figs. 5, 6 and 7 are side views, partly in section, illustrating different forms of handle parts.

The blade A, has at its butt end a toothed construction for coöperation with the blade holding sections and comprises teeth concentric with a bolt hole A', and comprising laterally projecting teeth A² around the blade A and projecting laterally from the face of the butt plate A³ and a series of radially projecting teeth A⁴ along the curved edge of the said butt plate as shown in Fig. 30. 2. These teeth A² and A⁴ enter corresponding notches B² and B⁴ in the inner faces of the cheek plates B³ of the blade holding sections B, the latter having central bolt holes B' which register with the hole A' in the butt plate A³ when the parts are assembled as shown in Figs. 1 and 3 of the drawing. The sections B are alike and have the cheek plates B³, the half bolts B⁵ of the two sections N combining to form a bolt to screw into the socket C⁷ of the handle as will be understood from Fig. 1 of the drawing. When thus screwed into the handle the bolt stem of the blade holding sections B may be secured to the handle by a cross bolt, as best shown in Fig. 3 of the drawings, the sections B being clamped together and upon the intermediate butt plate A³ of the blade A, by the clamping devices consisting, as shown, of the bolt E, as shown in Figs. 1 and 3 of the drawing. Manifestly by this construction, the blade A can be set to any desired angle and secured in such

position and thus be adapted for use in any manner desired.

The handle is shown as composed of sections united together by threading a tenon at the end of one section into a socket in the end of the adjacent section and I show in Fig. 5, a bent handle section F, and in Fig. 6 a grip section G, while in Fig. 7 I show a straight handle section I, and a short intermediate section J. Manifestly, these sections may be used interchangeably to adapt the knife for use as a scythe, as an ordinary cane cutter, and for use in close quarters. In the latter case the handle G, may be coupled directly with the handle C shown in Fig. 1. Manifestly, the thimble and brad construction as shown at the joint between the sections I and J in Fig. 7 may be employed if desired whenever two sections are jointed together.

I claim:

1. A cutter substantially as herein described comprising a blade having at one end a butt plate provided with a bolt hole and concentric therewith with curved series of laterally projecting teeth, and with teeth projecting radially from the free edge of the butt plate, blade holding sections having cheek plates provided with central openings to register with that in the butt plate of the blade, and having concentric sockets to receive the laterally and radially projecting teeth of the butt plate, the said cheek plates being provided with half-bolts adapted to lap side by side and combined to form a bolt, a handle having a socket receiving said bolt, and a clamping bolt passing through the concentric openings of the butt plate and the cheek plates and binding said plates together, substantially as set forth.

2. A cutter comprising a blade having a butt plate provided along its free edge with a curved series of radially projecting teeth, and having a concentric series of laterally projecting teeth on the opposite side of its center from said radially projecting teeth, and blade holding sections having cheek plates lapping on opposite sides of the butt plate and held thereto, substantially as set forth.

3. The cutter herein described comprising a blade having at one end a butt plate pro-

vided on its opposite sides with curved series of laterally projecting teeth and at its edge with teeth projecting radially from the free edge of the butt plate, blade holding sections having cheek plates provided with concentric sockets to receive the laterally and radially projecting teeth of the butt plate, the said cheek plates being provided

with means for connection with the handle and means for clamping the cheek plates to the butt plate, substantially as set forth.

ELDRED MARSHEL HIBBLER.
